(57) **CLAIM**

The ornamental design for an extensible frame for truck as shown and described.

DESCRIPTION

FIG. 1 is a front, left, top perspective view of an extensible frame for truck showing my new design;

FIG. 2 is a front, left, bottom perspective view thereof;

FIG. 3 is a front view thereof;

FIG. 4 is a left view thereof;

FIG. 5 is a top view thereof;

FIG. 6 is a bottom view thereof;

FIG. 7 is an enlarged view of the encircled area 7 of FIG. 1;

FIG. 8 is an enlarged view of the encircled area 8 of FIG. 2;

FIG. 9 is an enlarged view of the encircled area 9 of FIG. 3;

FIG. 10 is an enlarged view of the encircled area 10 of FIG. 3;

FIG. 11 is an enlarged view of the encircled area 11 of FIG. 5; and,

FIG. 12 is an enlarged view of the encircled area 12 of FIG. 6.

The back view thereof is a mirror image of the front view thereof, so the back view thereof is omitted.

The right view thereof is a mirror image of the left view thereof, so the right view thereof is omitted.

The broken lines shown on the drawings depict portions of the extensible frame for truck that form no part of the claimed design. The dot-dash lines depict the enlarged view boundaries that do not form part of the claimed design.
